UNITED STATES PATENT OFFICE.

MICHAEL DEERING, OF SYRACUSE, NEW YORK, ASSIGNOR TO CHRISTOPHER C. BRADLEY, OF SAME PLACE.

COVER FOR HEATING-FORGES.

SPECIFICATION forming part of Letters Patent No. 369,168, dated August 30, 1887.

Application filed February 28, 1887. Serial No. 220,155. (No model.)

To all whom it may concern:

Be it known that I, MICHAEL DEERING, of the city of Syracuse, in the county of Onondaga and State of New York, have invented 5 new and useful Improvements in Covers for Heating-Forges, of which the following is a specification.

This invention relates to the removable covers which form the tops of heating-forges. 10 These covers as ordinarily constructed consist of a number of fire-bricks and a metallic frame or band which encircles the bricks and holds the same together in the form of a rigid plate. The excessive heat to which these 15 covers are exposed expands the metallic frame or band, which causes the bricks to become loose and to fall out.

The object of my invention is to overcome 20 this difficulty; and it consists in the improvements which will be hereinafter fully set forth, and pointed out in the claim.

In the accompanying drawings, Figure 1 is 25 an end elevation of my improved cover applied to a heating-forge. Fig. 2 is an elevation at right angles to Fig. 1. Fig. 3 is a top plan view of the cover. Fig. 4 is a top plan view 30 of an extended cover. Fig. 5 is a fragmentary top plan view of my improved cover, showing a modified construction of the metallic frame.

Fig. 6 is a vertical section in line $\alpha\alpha$, Fig. 5. 35 Like letters of reference refer to like parts in the several figures.

A represents the upper portion of a heating-forge of usual construction.

B represents one or more rows of fire-bricks 40 or stone or other refractory blocks arranged in the form of an arch, which rests upon the forge on opposite sides of the hearth thereof.

C C represent the two portions of the metallic frame in which the arch of bricks B is secured. Each section C consists of a curved 45 metallic plate, which rests against the upper side of the arch and extends from the crown to the outer end thereof. Each plate C is provided at its outer edge with a downwardly-projecting flange, d, which bears against the end of the arch. The adjacent inner ends of the plates C C are connected by one or more movable joints, which permit the outer ends 50 of the plates to be adjusted toward and from

each other, as may be necessary to clamp the bricks securely.

As shown in Figs. 1, 2, 3, and 4, the movable joints are formed by perforated lugs e e, formed on the plates, and a pintle or bolt 55 passing through said lugs and forming therewith hinges on which the plates can swing.

In the construction represented in Figs. 5 and 6 the movable joints are formed by round knuckles f, formed on one plate, and engaging 60 in socketed or recessed lugs g, formed on the other plate. The two jointed plates are adjusted by one or more screws, h, passing through upwardly-projecting arms i, formed 65 on the plates near their inner edges, and provided with screw-nuts j, which bear against the inner sides of said arms.

Upon tightening the screw-nuts j the outer ends of the plates C are swung toward each other, thereby clamping the arch of brick and 70 forcing the latter upwardly against the concave lower sides of the plates C. This produces a close fit of the bricks in the metallic frame formed by the plates C, and holds the individual bricks closely against each other. 75 When the bricks show a tendency to become loose, the plates are easily adjusted to clamp the bricks securely.

The plates C C may be made of any desired 80 length. When the plates are comparatively short, as indicated in Figs. 3 and 5, two movable joints or hinges and a single adjusting-screw are sufficient for connecting the plates. When longer plates are used, as indicated in 85 Fig. 4, the number of movable joints and adjusting-screws are increased. Instead of forming a single long cover by extending the plates, as indicated in Fig. 4, a number of short covers may be arranged in line with each other. If the length of the arch of bricks varies some- 90 what by reason of the unequal size of the bricks, the frame is quickly adjusted to the length of the arch to be clamped.

I am aware that it is not new to clamp the 95 bricks between end plates which are pivoted to the outer ends of bars extending over the arch, and which are provided with an adjusting-rod, whereby the pivoted plates are clamped against the brick-work, and I do not claim such construction.

I claim as my invention—
In a furnace-cover, the combination, with
an arch of refractory blocks, of two metallic
binding-plates hinged together over the crown
5 of the arch, and constructed with concave
lower surfaces bearing against the upper side
of the arch, and provided at their outer ends
with rigid flanges which bear against the ends
of the arch, and near their inner ends with up-
wardly-extending arms connected by an ad-

justing device, whereby the end flanges are
pressed against the arch by separating said
arms, substantially as set forth.

Witness my hand this 12th day of February,
1887.

MICHAEL DEERING.
